UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S WATTEAU WRAPPER.

SPECIFICATION forming part of Design No. 14,482, dated December 11, 1883.

Application filed October 27, 1883. Term of patent 3½ years.

To all whom it may concern:

Be it known that I, MARY TURNER, of the city, county, and State of New York, have invented and produced a new and original Design 5 for a Pattern of a Lady's Watteau Wrapper, (numbered 8,917;) and I do hereby declare that the engraved prints accompanying this specification convey to any one accustomed to using paper patterns a clear understanding of how 10 a garment made up by the pattern will appear.

The design combines a vest-front slightly overlapped by loose-fitting side-fronts, and a

loose back with a double box-plait at the center, and a narrow deep yoke at the top. It is 15 short and round, and has pockets and coat-sleeves.

What I claim as my invention, and desire to secure by Letters Patent, is—

The design for a lady's watteau wrapper, as 20 shown in the engraved prints accompanying this specification.

MARY TURNER.

Witnesses:
